[57] CLAIM

The ornamental design for base part for artificial flowers or foliage, as shown.

DESCRIPTION

FIG. 1 is a perspective view of a base part for artificial flowers or foliage showing my new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof;

FIG. 8 is a reduced perspective view thereof, the artificial flowers or foliage shown in broken lines for illustrative purposes only and form no part of the claimed design.
